UNITED STATES PATENT OFFICE.

LOUIS ZIEGLER, OF LYNDHURST, NEW JERSEY.

PRACTICE-GUN.

1,265,984.

Specification of Letters Patent.

Patented May 14, 1918.

Application filed September 20, 1917. Serial No. 192,300.

To all whom it may concern:

Be it known that I, LOUIS ZIEGLER, a citizen of the United States, and a resident of Lyndhurst, county of Bergen, and State of New Jersey, have invented certain new and useful Improvements in Practice-Guns, of which the following is a specification.

My invention has for an object the provision of a practice gun which is fairly heavy and is adapted to be fired automatically when the trigger is pulled, and to emit gases and smoke at the muzzle, thereby giving an effect similar, in sound and appearance, to the firing of a real gun.

For practice purposes in the training of soldiers and for the training of organizations of younger persons, as boy scouts, and for the use of smaller children, wooden guns having the appearance of the usual soldier's rifle, but made of wood and very light, have been employed to a considerable extent.

Such guns, of course, cannot be fired, and their weight is so inconsiderable that they do not have the feel of the guns they are intended to imitate, and for this and other reasons it is difficult to create enthusiasm among persons supplied with these wooden guns.

In a gun in accordance with the present invention the part corresponding to the barrel of the ordinary gun is preferably made of metal, whereby weight is added, providing one feature of resemblance to the usual gun, and furthermore, since the gun is adapted to be fired and loaded for further firing automatically and to emit smoke and gases from the muzzle, a still further increased resemblance to the usual magazine gun is obtained which makes a gun in accordance with the invention very attractive to persons training for soldering and particularly to children playing soldier.

With the foregoing and related objects in view, my invention consists in the features of construction, parts, improvements and combinations herein set forth and claimed.

In the accompanying drawing forming a part of this specification, and wherein the same reference numerals are uniformly applied to designate the same parts throughout, I have illustrated an embodiment of my invention for the purpose of affording a clear understanding thereof, and in said drawing Figure 1 is a side elevation of a gun embodying my invention. Fig. 2 is a

perspective view of the wooden portion of the gun shown in Fig. 1. Fig. 3 is a perspective view of the metallic portion of the gun. Fig. 4 is a longitudinal central sectional view of the gun in the neighborhood of the muzzle and showing the working parts. Fig. 5 is a fragmentary perspective view of an operating finger and the end of the hammer operated thereby, and Fig. 6 is a transverse cross-sectional view illustrating the operation of the magazine loading device.

Reference numeral 10 indicates the wooden part of the gun which in the form shown comprises a stock 11 and an extending portion 12 recessed to receive the metallic portion 13 of the gun corresponding to the usual barrel, the recess having preferably the form shown at 14, Fig. 2.

The part 13 is generally of tubular form and may be made up from tubing or may be stamped from sheets or constructed in other ways, as, for example, it may be made up of a channel bar 13' and an angle bar 13''. The interior thereof is hollow and the open slide-way 15 is provided, preferably on one side thereof, for receiving the projecting handle 16 of the slide member 17. An opening 18 is formed at the rear of the member 13 which may be closed by a cover 19 pivoted at 20 and having its point 21 adapted to be received and held under a spring catch 22 which also is preferably provided with a notch 23 to form the rear sight. The slide member 17 is provided with a forwardly and upwardly projecting leaf spring 24, and when the slide member 17 is retracted to the breech of the gun a roll of tape containing caps or other explosive charges spaced at intervals therein, may be introduced into the opening 18 and its forward end passed over the end of the spring 24, whereupon the slide 17 may be pushed toward the muzzle by means of the handle 16, thereby unrolling the roll of cap tape and loading the gun, the unrolled portion of the tape occupying the position shown by the dotted line 25, Fig. 4, and being extended lengthwise in the gun barrel. The handle 16 may be locked in its forward position by means of the catch 26 pivoted on the barrel 13, and said catch 26 may carry an upwardly extending pointed device, as illustrated at 27, which may form the front sight for the gun. The spring 24, after serving to carry the tape forward as

already described, also serves, when the slide 17 is locked in forward position, as a means for preventing the tape being drawn backward, as will be clearly seen in Fig. 4.

The trigger 28 serves, when it is actuated by the finger of the user, to feed forward the tape 25 and also to operate means for exploding charges therein. In the form shown a hammer 29 is pivoted at 30 and is driven by a spring 31 against the anvil 32 at the muzzle of the gun, and a longitudinally movable rod 33 is pivoted to the upper end of the trigger at 34, and a spring 35, preferably coiled about the rod 33, serves to retract the same and to bring the trigger to normal position after the gun is fired. The rod 33 has formed thereon or is connected to a slide member 36 which is guided in suitable ways and is provided with a finger 37 having a cut-away part 38 (Fig. 5) and adapted to coöperate with a preferably rounded lug 39 on the hammer 29. As the trigger is pulled the finger piece 37, advancing under the lug 39 on the tail piece of the hammer 29, moves the hammer 29 away from the anvil 32 and at the same time the spring 40 on the slide 36 engages the tape and advances it, the spring 24, as already explained, preventing rearward movement of the tape when the spring 40 is moved backward. When the finger 37 has passed sufficiently under the lug 39 so that said lug enters the cut-away part 38, the hammer is released and is driven against the anvil 32 by means of the spring 31, thereby exploding the charge. The springs 24 and 40, or either or both of them, serve to prevent flame or sparks from passing rearward through the barrel so that there is no opportunity for other charges than that exploded to be ignited and the device is rendered entirely safe. In returning to normal position the finger 37 rides over the lug 39. This can be accomplished in various ways. For example, if the finger 37 is fairly rigid, as is preferably the case, the opening 33' for the rod 33 may be made somewhat larger than the rod so that the same may move upward somewhat on returning to normal, the spring 40 serving at other times to hold the finger 37 and rod 33 in downward position as shown in Fig. 4, or the finger 37 may have sufficient flexibility so as to bend a sufficient amount to override the lug 39 during its return movement.

The device can be readily assembled, as, for instance, the parts constructed of metal 60 may be secured together by screws 41, 42 and when fastened together, may be secured in the wooden part of the gun by means of the screw 43 at the rear end thereof, and a clamping sleeve 44 at the muzzle of the gun 65 which, if desired, may be secured in place

by means of the screw 45. To take the gun apart it is only necessary to remove the various screws and the sleeve 44, whereupon the parts shown may be readily disassembled and as readily reassembled.

The operation of the gun will be readily understood from the foregoing. The roll of cap tape is introduced into the opening 18 and engaged by the spring 24 by which it is held, and is drawn forward by movement of the slide 17. The magazine cover may now be closed and the gun is ready for firing, which is accomplished by pulling on the trigger 28, thereby moving forward the spring 40 and finger 37 and operating the hammer 29 and also simultaneously feeding the tape forward by successive engagements of the spring 40 therewith, the spring 24 meanwhile serving to prevent the tape from being moved backward.

It is to be understood that the form shown is intended only to illustrate my invention, and that I am not to be confined thereto, but that changes therefrom and modifications therein may be made within the scope of my claims without departing from my invention or sacrificing its advantages.

I claim:

1. In a practice gun, an anvil, a hammer pivoted therebeneath, a spring for pressing said hammer toward said anvil, a trigger, a slidable means for actuating said hammer, and connecting means between said slidable means and trigger and extending longitudinally of the gun.
2. In a practice gun, a trigger, an anvil and a hammer located adjacent to the gun muzzle, a slidable member for actuating said hammer, and a rod extending longitudinally of the gun and connected respectively to said slidable member and to said trigger.
3. In a practice gun, means at the muzzle for exploding charges in cap tape, a barrel extending rearwardly therefrom, and means including a slide and slide-way for feeding the tape through the barrel to the explosion means.
4. In a practice gun, a barrel provided with an opening adjacent to its rear end, a slide in said barrel, said slide being adapted to propel a strip of cap tape introduced into said opening through the gun barrel, and means adjacent to the gun muzzle for exploding the charges in said cap tape.
5. In a practice gun, a barrel, means comprising a spring for drawing cap tape through the barrel, means for holding said means in its advanced position, said spring acting in such position to prevent reverse movement of the tape, a hammer, a trigger, and means operated by said trigger for engaging and advancing a strip of cap tape when so held.

6. In a practice gun, an elongated gun barrel, slideable means comprising a spring for advancing the tape in the barrel, and trigger-actuated means also comprising a 5 spring for automatically feeding forward the tape upon actuation of the trigger.
7. In a practice gun, an elongated gun barrel, means adjacent to its muzzle for exploding charges in cap tape fed through said 10 barrel, actuating means therefor, and means connected with said actuating means for feeding said cap tape forward to the exploding means.
8. In a practice gun, a barrel having a 15 slide-way therein, a slide in said barrel having a handle projecting through said slide-way, a spring on said slide member adapted to engage and advance a strip of cap tape through the barrel, and means at the muzzle 20 for exploding the charges in said cap tape.
9. In a practice gun, a barrel, means for advancing a strip of cap tape through the barrel, and locking means for said means, said locking means also forming a sight for 25 the gun.
10. In a practice gun, slideable spring means for advancing a cap tape and holding it in advanced position, and reciprocable spring means for engaging said cap tape be-
- yond said first named spring means and 30 feeding it forward, said first named spring means serving to prevent the retrograde movement of said cap tape.
11. In a practice gun, a barrel composed of a channel strip and an angle bar, there 35 being a slide-way left between the walls of the channel strip and angle bar, a slide member within the barrel formed between the said bars, and a handle projecting through said slide-way, a trigger, and means at the 40 muzzle end of the gun actuated by said trigger for exploding charges in a strip of cap tape fed forwardly through the barrel by said slide member.
12. In a practice gun, an anvil, a hammer 45 pivoted between its ends and having a lug on the end opposite the striking end thereof, a slide member having a projecting finger and a cut-away part on one side thereof, and means comprising a trigger for reciprocating said slide member whereby said hammer is actuated by said finger engaging said lug, 50 said lug being released when it enters the said cut-away portion of the slide member.

In testimony that I claim the foregoing, I 55 have hereto set my hand, this 19th day of September, 1917.

LOUIS ZIEGLER.
